UNITED STATES PATENT OFFICE.

FRIEDRICH TUECKE, OF LEECHBURG, PENNSYLVANIA.

CIGAR-PERFORATOR.

SPECIFICATION forming part of Letters Patent No. 317,247, dated May 5, 1885.

Application filed December 26, 1884. (No model.)

To all whom it may concern:

Be it known that I, FRIEDRICH TUECKE, a citizen of the United States, residing at Leechburg, in the county of Armstrong and State of Pennsylvania, have invented certain new and useful Improvements in Cigar-Perforators; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 In order that a cigar may be smoked it is necessary that its end be cut off or perforated, so that it may draw. Ordinarily the end of the cigar is cut off, and various devices are in use for cutting off the end. The chief objection 20 to thus cutting off the end is that the wrapper of the cigar which is cut through unwinds and so prevents the cigar from drawing well. To obviate this objection, a hole is punctured in the end of the cigar, which affords sufficient 25 passage for the smoke.

This invention consists in an improved device for puncturing such a hole in the end of a cigar, and it is illustrated in the accompanying drawings, in which—

30 Figure 1 is a central vertical longitudinal section of the device, and Fig. 2 is a central vertical cross-section of the same.

Like letters designate corresponding parts in both figures.

35 A base, A, supports a box, B, in which slides a block, C, which is held therein. A puncturing-pin, D, is fixed to the block and passes upward through an aperture, a, in the cover E, which is fastened to the top of the 40 box. The block C is raised by means of a lever, F, which passes through a slit, b, in the frontside of the box, and which is pivoted in said slit. The inner end of the lever F enters a slot or recess, e, in the block, and a

downward movement of the lever raises the 45 block. A coiled spring, G, around the pin D, and held between the block C and cover E, returns the block after it has been raised to its normally depressed position.

Secured to the cover E is a cup, H, which 50 is shaped to receive the end of a cigar. At its bottom it is provided with an aperture, f, through which the pin D passes when the block C is raised. The point of the pin normally rests below the bottom of the cup H. 55

When it is desired to perforate or puncture a cigar, its end is inserted in the cup H, the lever F is then depressed, thus raising the block and driving the pin D into the end of the cigar. The lever F being relieved of pressure, the spring G depresses the block and pin, and the punctured cigar is then removed.

I am aware that it is not new to puncture the end of a cigar by means of a pin carried by a block, which enters a cup-shaped receptacle in which the end of the cigar is placed, and I make no claim to such a device; but

What I do claim is—

The combination of base A, box B, provided with a slit on one side, block C, which 70 slides up and down in said box, and is provided with a slot or recess, a puncturing-pin, D, fixed to said block, box-cover E, provided with an aperture through which said pin passes, lever F, which passes through the slit in 75 the box and is pivoted therein, and the inner end of which enters the slot or recess in the block, spring G, between the block and cover, and a cup, H, secured to the cover and provided with an aperture in its bottom, through 80 which the pin passes when the block is raised, substantially as set forth.

In testimony whereof I affix my signature in presence of two witnesses.

FRIEDRICH TUECKE.
